UNITED STATES PATENT OFFICE.

FRANKLIN GREAR NEAL, OF HALIFAX, NOVA SCOTIA, CANADA.

ROOF CONSTRUCTION.

1,112,717.

Specification of Letters Patent. Patented Oct. 6, 1914.

Application filed November 15, 1912. Serial No. 731,594.

To all whom it may concern:

Be it known that I, FRANKLIN GREAR NEAL, residing at Halifax, in the Province of Nova Scotia, Canada, a citizen of the United States of America, have invented certain new and useful Improvements in Roof Construction; and I do hereby declare that the following is a full, clear, and exact description of the same.

This invention relates more particularly to the construction of metallic roofs, being intended primarily for application to the roofs of box-cars and the like although it will be understood that it may be applied with advantage to the roofs of other structures.

The invention has for an object to provide an improved and simplified means of attaching the metal sheets of the roof to each other and to the framework of the roof.

For further comprehension of the invention and of the objects and advantages thereof reference will be had to the following description and appended claims, and to the accompanying drawings forming part of this specification in which similar reference characters indicate the same parts and wherein,

Figure 1 is a plan view of a portion of a roof embodying the invention. Fig. 2 is a transverse section thereof taken on the line 2-2 Fig. 1. Fig. 3 is an enlarged detail side elevation showing particularly one of the joints between the roof sections. Fig. 4 is a section on the line 4-4 Fig. 3, the view being taken longitudinally of the joint and transversely of the roof. Fig. 5 is a section on the line 5-5 Fig. 4 looking in the same direction as Fig. 3.

My improved roof comprises a plurality of sheet metal sections 2 which preferably (as shown in Fig. 1) extend the full width of the roof and are laid upon a suitable frame work, the invention being here shown as applied to the roof of a box car and the framework as comprising longitudinal side beams or side plates 3 and transverse supports or carlines 4, the side beams consisting of angle bars with their flanges turned outwardly from their top sides while the transverse supports are made of T-beams

with downturned flanges. The side edges of the roof sections or sheets are bent downwardly over the horizontal flanges of the side beams as shown at 2' while rivets 2^a secure the sheets to the side beams and carlines. The adjacent edges of these sections are supported upon the carlines and are turned upwardly and slightly backwardly as at 3' and cover or locking strips 4' having downwardly and inwardly projecting flanges 5 are slipped over the flanges 3', the flanges 5 on the strips terminating at the edges of the roof and the flat ends bent around under the outturned flanges of the side beams as at 10 and rivets 11 passed through these ends 10, the flanges of the side beams, and the main body of the cover strips to hold the latter in position. The dovetail arrangement of the upturned and downturned flanges 3' and 5 (which is clearly shown in Fig. 5 of the drawings) serves to lock the cover strip in position without any further attachments and provides a rain proof joint between the roof sections.

What I claim is as follows:

1. In car roof construction, the combination with longitudinal side beams and metal roof sections, of a transverse cover strip covering the adjacent transverse edges of the roof sections and having its ends turned downwardly across the longitudinal edges of said beams and bent inwardly beneath the latter and rivets passing through the beams and through the strip above and below said beams.

2. In car roof construction, the combination with longitudinal side beams and metal roof sections having their transverse edges turned upwardly, of a transverse cover strip overlapping the edges of the roof sections and having its ends turned downwardly across the longitudinal edges of said beams and cover strip and bent inwardly beneath said beams and rivets passing through the beams and through the strip above and below said beams.

3. In car roof construction, the combination with longitudinal side beams and metal roof sections having their transverse edges turned upwardly and their longitudinal edges bent downwardly across the longitudi-

nal edges of said beams, of a transverse cover strip overlapping the edges of the roof sections and having its ends turned downwardly across the longitudinal edges of said beams and cover strip and bent inwardly beneath said beams and rivets passing through the beams and through the strip above and below said beams.

In testimony whereof, I have signed my name to this specification, in the presence of 13 two subscribing witnesses.

FRANKLIN GREAR NEAL.
